UNITED STATES PATENT OFFICE.

JOHN MOORE, OF WINNIPEG, MANITOBA, CANADA.

CALF-FEEDER.

1,127,797.

Specification of Letters Patent.

Patented Feb. 9, 1915.

Application filed November 18, 1912. Serial No. 731,958.

To all whom it may concern:

Be it known that I, JOHN MOORE, of the city of Winnipeg, in the Province of Manitoba, Canada, have invented certain new and useful Improvements in Calf-Feeders, of which the following is the specification.

The invention relates to an improvement in calf feeders and the object of the invention is to provide an inexpensive, durable and efficient device whereby one can readily feed young animals a particular feature being that the device is constructed to present a form very similar to the shape of an udder and teat so that natural conditions are closely approached.

With the above objects in view the invention consists essentially in a specially designed connecting piece, a feed tube carried by the connecting piece, a nipple mounted on the connecting piece and a plurality of clamping members securing the nipple to the connecting piece, the parts being arranged and constructed as hereinafter more particularly described.

Figure 1 is a side view of the complete device as applied on a can. Fig. 2 is a plan view of the same. Fig. 3 is an enlarged detailed vertical sectional view centrally through the device and a portion of the upper part of the can. Fig. 4 is a front view of a number of the devices as they appear in a second embodiment of my invention. Fig. 5 is a vertical sectional view through the supporting boards, the section being taken in the plane denoted by the line Z—Z' Fig. 4 and looking in the direction indicated by the arrow "b". Fig. 6 is a vertical sectional view through the device the section being taken in the plane denoted by the line Y—Y' Fig. 4 certain parts being shown in side elevation. Fig. 7 is an enlarged detailed vertical sectional view centrally through the nipple, the connecting piece and clamping members as they appear in the second embodiment of the invention. Fig. 8 is a horizontal sectional view through the connecting piece the section being taken in the plane denoted by the line X—X' Fig. 7. Fig. 9 is a side view of the connecting piece.

In the drawings like characters of reference indicate corresponding parts in each figure.

Referring now particularly to Figs. 1, 2, 3 and 9 of the drawings:

1 represents a can or receptacle for the re-

ception of milk or other such liquid which can is shown in the present instance with a conical top 2 provided with an exteriorly threaded neck 3. The can is supplied with a handle 4.

5 represents my connecting piece which has the body portion 6 thereof fitted with a circumferentially directed groove 7 forming a beading 8 at the top and a shoulder 9 at the bottom the purpose of which will be later explained. The body portion is also supplied with an extending interiorly threaded flange 10 and an extending exteriorly threaded tube 11 there being a continuous duct 12 passing through the tube and body portion. The thread on the flange is arranged so that the connecting piece can be screwed onto the neck and the thread on the tube is supplied to receive the threaded end of the feed pipe 13.

14 represents a rubber or such like flexible nipple having the upper end thereof supplied with a feed opening 15 and the lower end thereof slipped over the connecting piece, the base of the nipple resting in the groove 7 between the beading 8 and the shoulder 9.

16 represents a holder for the can. The holder is formed from the following parts: 17 represents a base formed from two sections 18 and 19 connected by hinges 20. 21 is the top of the holder formed from two strips 22 and 23 arranged to fit around the top of the can 1.

The top and base are connected by upright 90 bars "a".

24 and 25 are similar spherical segments forming clamping members provided each with out-turned flanges 26 permanently secured by screws 27 or such like to the strips 22 and 23 or the top of the holder. These members are each fitted with in-turned flanges 28 and 28' arranged to receive the connecting piece and the flanges are supplied with ribs 29 and 29' adapted to jam the base 100 of the nipple into the groove between the beading and the shoulder.

The strips forming the top piece carry any suitable means whereby they can be fastened together, that shown comprising hooks 105 30 and eyes 31.

When the device above described is to be used the holder is opened by undoing the hooks and the can is inserted within the holder. The holder is then closed and 110

locked on the can and when this is done it is found that the nipple is securely fastened to the connecting piece by the clamping members. The calf will quickly take to the feeder as the nipple and clamping members conform very closely to the actual shape of a cow's udder and teat.

In the remaining figures of the drawings I have shown a second embodiment of the invention wherein the holder has been dispensed with and the device fitted up so as to feed a number of animals. The individual can is dispensed with and a common can which feeds all the nipples is supplied.

In Figs. 4, 5, 6, 7 and 8 of the drawings I have retained the same reference characters on the parts which are the same as those described in Figs. 1, 2, 3 and 9. The coupling piece, feed tube, clamping members and nipple are all the same. The holder has been entirely dispensed with and in its place I have supplied the following parts:

32 and 33 represent two boards carried by the end pieces or standards 34 and 35 and the standard 34 carries a platform 36 which supports a common feed can 37. A pipe 38 leads from the can to the rear of the boards which pipe is supplied with a controlling valve 38'. The top board 33 is provided with a plurality of grooves 39 having V-shaped ends which grooves receive slidably plates 40 having their forward faces in the same plane as the boards and their lower edges abutting the upper edge 35 of the lower board.

The plates carry each a clamping member 24 while the board 32 carries a number of the clamping members 25, the clamping members carried by the plates and board 40 being arranged so that they close together in pairs in each instance when the plates are closed in.

Any suitable means can be employed for fastening the plates in their inner positions,

hooks and eyes being shown in the drawings.

A plurality of feed tubes 13 pass from the common feed pipe 38 and pass between the boards the outer ends of the tubes being fitted with connecting pieces 5 carrying 50 the nipples 14.

When the device above described is set up or assembled and the plates 40 are locked by the hooks and eyes, the top clamping members jam down on the lower clamping members and catch the nipple in the same manner as is done where the holder is employed.

I have only shown the device as arranged to feed four animals but it will be understood that the number could be increased indefinitely to feed any number of calves.

In actual practice it would no doubt be unnecessary to provide a special stand to carry the clamping plates as they could be 65 suitably arranged on a manger or in any other desirable location.

What I claim as my invention is:—

In combination, a feed pipe, a connecting piece having a depending threaded central 70 tube, adapted to be connected to said feed pipe, said connecting piece being provided with a central duct and having a circumferentially directed groove formed on the outer side thereof and a nipple fitted on the connecting piece, said nipple having a depending flange, spherical clamping members having inturned segmental flanges, said segmental flanges engageable with the first mentioned flanges and ribs on said segmental flanges, and outturned apertured flanges on said clamping members.

Signed at Winnipeg, this 20th day of August 1912.

JOHN MOORE.

In the presence of—

G. S. ROXBURGH,
P. FOSTER.
